UNITED STATES PATENT OFFICE

ALBERT F. BEMIS, OF NEWTON, MASSACHUSETTS, ASSIGNOR TO BEMIS INDUSTRIES, INCORPORATED, OF BOSTON, MASSACHUSETTS, A CORPORATION OF DELAWARE

BUILDING FRAME

Application filed April 30, 1929, Serial No. 359,209, and in Great Britain March 22, 1929.

This invention pertains to an improved form of building construction, and more particularly to a structural framework and the arrangement of the same in conjunction with related parts. A somewhat similar arrangement is shown in my copending application, No. 266,955, filed April 3, 1928, of which the present application is a continuation in part.

The present invention provides improved frame members, such as posts, studs, girts, and sills, each of which preferably may be formed of a plurality of elongate structural elements that may be so combined and arranged as to facilitate the assembly of the structural framework and the convenient attachment of the adjoining parts and subsequent finish thereto. The preferred form of girts, posts, studs, etc. with parallel flanges defining the outer faces of the structural wall permits the metal frame members effectively to receive the imposed loads and strains and facilitates the application of layers of finishing material such as panels, stucco, plaster, sheathing, etc.

This arrangement particularly lends itself to the use of structural members formed of standardized dimensions, for example, as described in my copending application, No. 280,226, filed May 24, 1928, with means to engage fastening or other building parts located at modular distances; accordingly, the frame members may be manufactured in quantities in an establishment particularly adapted for this purpose and may be rapidly assembled in situ without requiring a high degree of skill or particular accuracy upon the part of the workman erecting the framework.

In the accompanying drawings: Fig. 1 is a broken plan view of a portion of a framework of a building constructed in accordance with the present invention;

Figs. 2, 3, 4 and 5 are sections on lines 2-2, 3-3, 4-4 and 5-5, respectively, of Fig. 1;

Fig. 6 is a corresponding section showing a different form of stud;

Fig. 7 is a sectional detail of the connection between the structural frame and the rafters;

Fig. 8 is a side elevational view showing one manner of incorporating a stud in framework of this character;

Fig. 9 is a perspective view showing columnar units utilized in connection with a frame of this character; and

Fig. 10 is a perspective detail of an optional form of girt member.

In the accompanying drawings, the numeral 1 indicates the base, footing, or foundation upon which a building is to be constructed. In accordance with this invention, the metal framework may be either erected upon the footing itself and the foundation be poured about the metal framework to afford a metal reinforced foundation, for example, as described in my copending application, No. 342,996, filed February 27, 1929, or the foundation may first be poured or otherwise constructed, and the metal framework be erected above the same. The sill members 2 which are directly mounted upon the base 1, each comprise a web plate 4, and structural elements 3 secured to the upper face of the plate at either side thereof by welding, or the like, the elements 3, as shown, may preferably be separate angles. The sill is provided with a plurality of intermediate longitudinally disposed openings 6, and may be secured in place by pouring of cementitious material over these openings so that the sill is firmly secured to the base as the cementitious material or grouting sets. The upright members of the framework are then secured to the sills, these uprights comprising suitable studs 10 or 10^a and posts 20, 21 or 22.

As shown in Fig. 3, studs 10 may be formed of spaced parallel angles 12 which are connected at intervals by channels 14. The latter preferably are welded to the angles, being disposed at the ends of the same as well as ordinarily at one or two points therebetween. The channels preferably project beyond the ends of the angles to interfit with the upstanding flanges 5 upon the sill members 2 and to engage corresponding portions of the girts at the upper ends of the studs, while the ends of the angles 12 engage the edges of the flanges of the angles 3. Each leg of

a channel 14 is provided with a suitable opening that is adapted to register with one of the openings 17 which are disposed at stand-
ardized intervals upon the upstanding flanges
5 of the angles 3 of the girts. Suitable fasten-
ing means, such as bolts 19, may be utilized
to secure the studs to the sills.

The posts which occur at the intersections
10 or corners of walls preferably are built up
of a plurality of stud members of the type
described above; these elements are arranged
at right angles to each other with their
flanges aligned with flanges of the sills and
15 girts of the intersecting walls, as shown in
Fig. 1, and are connected to each other by
angles 24 or the equivalent. Accordingly,
the post 20 at a corner formed by two walls
is built up of two stud members, the post 21
20 at the meeting point of three walls is made
up of three stud members, while the post 22
which interconnects four walls is formed of
four stud members.

Girts 26 may be formed of two pairs of
25 angles 3 similar to the corresponding por-
tions of the sill members, these angles being
located, however, both above and below an
intermediate web plate 28 which is provided
30 with central longitudinally disposed open-
ings 29, and which may project outwardly
beyond one or both sides of the framework
to form a ledge or ledges 30 in order to sup-
port floor joists or the like upon one or both
35 sides of the wall, if desired. Girts 26 are
connected to the studs and posts by means
of channels 14 and fastenings 19 in the same
manner as described with reference to the
sill elements, the angles 3 of the girt being
40 provided with modularly spaced openings 17
similar to those in the angles 3 of the sill
elements. The outstanding flanges 30 of the
girt elements are provided with openings 31
45 which are spaced at modular distances, and
receive fastening elements 33 such as drive
screws to engage the floor joists 35 or the
like supported thereby; the ends of these
flanges are preferably beveled, as designated
50 by numeral 40, to facilitate assembly. Prefer-
ably the girts for the outer walls are all
provided with inwardly extending flanges 30
so that the floor joists may run in either
55 direction as desired.

Fig. 2 illustrates a girt 26 having ledges 30
extending at each side of the girt to engage
55 joists 35 when the girt supports floors at each
side of the wall in which it is located.

Fig. 3 shows more particularly a girt of this
character which is provided with one ledge
30 to support joists 35 at one side of the wall;
while Fig. 4 shows a girt of the type which
60 is used with non-load bearing walls, for ex-
ample, walls parallel to the floor joists.

It is evident that this metal framework
may be continued upwardly for succeeding
65 stories, the posts and studs for the same being
connected to the upper pair of angles of the

girts for the first story in the same manner
that the studs and posts were connected to the
sill members.

Fig. 7 shows a girt 126 which may be used
to permit the connection of rafters 70 to the
70 vertical wall. For this purpose, the girt 126
is provided with a single pair of angles 3
which are secured to the upright members of
the framework in the same manner as pre-
75 viously discussed, while a web plate above the
angles affords, if desired, an inwardly pro-
jecting ledge 30.

A wooden plate 138 may be disposed upon
the girt 126 being secured thereto by screws
33 projecting from the ledge 30. Rafters 70
80 may be provided with notches 137 engaging
the plate 138, while the joists 135 may also be
riveted to engage the latter. Preferably the
rafters and joists may be disposed in jux-
85 taposition and connected by fastening ele-
ments 140 in the conventional manner.

The openings 29 in the girts permit the
pouring of cementitious material into spaces
in the walls as finally formed, for example, as
90 shown in Fig. 9, a girt of the type illustrated
herein may be combined with wall units 36
of the character disclosed in my pending
United States application, Serial No. 72,675,
95 filed December 2, 1925, these units being ar-
ranged to afford parallel vertically disposed
spaces 37 which are adapted to register with
the openings 29 in the girt to permit the pour-
ing of concrete 41 into the channel formed
100 between the angles upon the upper portion of
the girt with integral extensions 42 of this
concrete located within the spaces 37 to pro-
vide vertical reinforcements for the wall.

Fig. 6 shows one manner in which wooden
105 studs 10^a may be incorporated in a metal
framework of the character disclosed here-
with, these studs receiving substantially hori-
zontal screws or fastening elements 50 which
110 pass through the openings 17 in the sill mem-
bers and in the lower pair of angles in the
girts 26. It is obvious that any suitable lat-
eral bracing may be applied to a frame of this
character if desired.

Fig. 10 shows a slightly different type of
girt member which is formed of a pair of
115 channels 65 having their bight portions weld-
ed or otherwise secured to an intermediate
web plate 28 and affording intermediate open-
ings 29^a for pouring concrete or the like. It
120 is obvious that openings 17^a and 31 may be
provided in the outstanding flanges of the
channels and web plate respectively for con-
nection with the frame elements of intersect-
ing walls.

As explained more in detail in my copend-
ing application, Serial No. 280,226, filed May
24, 1928, the elongate frame members such
as the girts and sills preferably may be pro-
vided in standardized lengths which differ
from each other by the modular dimension,
125 (or by a multiple of the same) i. e., by the
126

width of these frame members as defined by the distance between their parallel flanges. Accordingly a building of any desired floor plan may be constructed of the standardized frame members without necessity of cutting the same to special lengths. Thus, for example, the number of inner walls between different portions of opposite outside walls may differ since the portions of such inner walls which are interposed between the ends of horizontal frame members have a thickness or depth equalling the differences between lengths of the horizontal frame members. Openings 17, 29 and 31 are all spaced at the same modular intervals from each other or at multiples of the same, these modular intervals ordinarily corresponding to the width of the structural framework as defined by the outer faces of the angles 3 and 12. This arrangement permits the rapid assembly of the parts in situ and proper locating and rapid connection of the secondary frame elements such as studs, joists or rafters which may also be of standardized lengths, and which are readily disposed at standardized distances from each other.

I claim:

1. A building construction comprising a horizontal set of frame members, a vertical set of frame members including posts at wall intersections and studs between the posts, the posts having parallel flanges projecting outwardly in the direction of each intersecting wall, the horizontal frame members having flanges substantially in the planes of the flanges of the posts, the flanges of one of said sets of frame members terminating substantially at the edges of flanges of the other set of frame members, and sheet metal connecting elements disposed between the adjoining portions of the flanges of said members and being secured in interfitting engagement therewith.

2. A building construction comprising horizontal frame members, certain of said members each including a web plate, a pair of angles having legs in aligned engagement with a face of the plate, and their other legs disposed in parallelism at right angles thereto providing flanges, and vertical frame members connected to said flanges, the web plates of the frame members projecting beyond the angle to comprise a ledge, said ledge having openings providing connections with horizontal frame members, said openings being spaced at integral multiples of a modular dimension determined by the width of the frame member between the parallel flanges.

3. A building construction comprising girt members, certain of said girt members comprising a web plate, a pair of angles having legs secured to one of the faces of the web plate with their other legs projecting in parallelism at right angles thereto pro-

viding flanges, and a corresponding pair of angles having legs secured to the other face of the web plate and similarly disposed relative thereto, stud members comprising spaced angles, each having one of their legs disposed in the plane of one of said flanges, and connecting elements engaging said flanges and the legs of the stud members.

4. A building construction comprising stud members, girts comprising a web plate and a pair of angles having legs in aligned engagement with a face of the plate and their other legs projecting in parallelism at right angles thereto providing flanges, one of the longitudinal edges of the web plate projecting beyond the angles to provide a ledge, connecting elements engaging said flanges and the stud members, and joists supported by and secured to the ledges of said girts.

Signed by me at Boston, Massachusetts, this 25th day of April 1929.

ALBERT F. BEMIS.
